CLAIM

The ornamental design for a housing for a mobile computing device, as shown and described.

DESCRIPTION

FIG. 1 is a leftward front isometric view of a housing for a mobile computing device showing the new design;

FIG. 2 is a rightward front isometric view of the housing for the mobile computing device of FIG. 1;

FIG. 3 is a front view of FIG. 1;

FIG. 4 is a leftward side view of FIG. 1;

FIG. 5 is a rightward side view of FIG. 1;

FIG. 6 is a bottom end view of FIG. 1; and,

FIG. 7 is a back view of FIG. 1.

In the drawings, the long dashed lines and the short dashed lines indicate unclaimed portions of the housing for a mobile computing device and form no part of the claimed design.

1 Claim, 6 Drawing Sheets
